SHEET METAL BENDING BRAKE FOR
MAKING S-CLIPS

Burris R. Allen, Detroit, Mich.

Application December 9, 1947, Serial No. 790,558

10 Claims. (Cl. 153—4)

1

The present invention relates to certain new and useful improvements in a portable hand-operated sheet metal bending brake which, while useful for bending and forming other articles, is especially adapted to shape and form so-called S-clips such as are used in connection with air duct constructions and other installations in air conditioning systems.

One object of the invention is to provide a sheet metal bending machine of the kind above referred to which, although usually simple from a mechanical structural standpoint, is of the utmost efficiency in expeditiously making an S-clip through the medium of holding and bending means which is set into operation by simply grasping and swinging a hand lever in a direction away from the user and then returning it to the initial or starting position.

Another object of the invention is to provide a highly practical and useful S-clip making machine which is so constructed that the flat sheet of stock may be readily placed in position in the principal work holding member, oscillated or rocked in one direction, then swung back to its original position, during which steps the bending results are obtained and after which said stock, in the form of the completed S-clip, may be quickly lifted, by hand, from said work holding member.

A further object of the invention is to structurally, functionally, and otherwise improve upon sheet tin bending and forming brakes through the adoption and use of a simple frame, said frame being provided with three spaced parallel, horizontally disposed bars, the latter being mounted for oscillation in bearings in the frame and being rocked toward and from each other by positive and suitably timed gearing in a manner to successively and progressively bend one edge of the strip stock during the first step and to then reversely bend the other edge of the same strip upon completing the second step.

Other objects and advantages will become more readily apparent from the following description and the accompanying illustrative drawings.

In the drawings, wherein like numerals are employed to designate like parts throughout the views:

Figure 1 is a plan view of a sheet metal bending brake constructed in accordance with the present invention.

Figure 2 is a right end elevation of the showing of Figure 1.

Figure 3 is a fragmentary cross sectional view

2

illustrating the parts in the positions assumed at the first stage of operation.

Figure 4 is a cross section taken on line 4—4 of Figure 1, like Figure 3, but showing the coacting parts in the relative positions assumed in the second stage of operation, that is, the first bending step.

Figure 5 is a cross sectional view which appears the same as Figure 3 except, at this third stage, the second bending step, which serves to finish the S-clip, is completed.

Figure 6 is a fragmentary sectional view on the line 6—6 of Figure 5, looking in the direction of the arrows.

Figure 7 is a fragmentary perspective view showing a finished so-called S-clip.

Briefly, my novel S-clip brake is characterized by two vertical frame members or uprights having bearings in which the shaft-ends of three simple bars are journaled for rotation. All of the bars are suspended in substantially the same plane in close spaced parallelism. Three identical gears provide a simple gear train and are lined up in contact with the exterior side of one frame member, are fixed on the respective three journals or stub-shafts at this end of the structure and these gears are in the same plane and substantially level with said bars. A single handle is attached to one journal and is swung first away from the operator and then immediately returned to its starting position and this is all that is necessary to accomplish the complete two-way bending and folding result. To attain this, reliable facilities of suitable shapes and in timely ordered positions, are provided on said bars. Thus, two uprights, three bars, three gears, a single handle and simple expedients on said bars serve to provide a simple, economical and practical special purpose bending brake.

The machine is supported by a simple portable frame which embodies a pair of rectangular plates or uprights 9 and 10. Mounted in suitable bearings in the left hand upright 9 are stub shafts 11, 12 and 13 carrying intermeshing gears 14. At the opposite end of the structure the upright 10 is provided with stub shafts 15, 16 and 17 geared together by coacting gears 18. A handle 19 is securely fixed to the extending end portion of the stub shaft 17 and constitutes the sole part for simultaneously operating all of the stub shafts and gear trains.

The principal work holding unit or part may be conveniently identified as a work holding, turning and forming mandrel or bar 20. This is polygonal in cross sectional form and has one

surface or face 21 cut away and beveled to provide for clearance in a manner to be hereinafter described. Another face of said bar is rabbeted or grooved as at 22 to accommodate a retention plate 23 for the sheet of tin or other work-piece 24. The plate 23 coats with the groove in defining a pocket for a one-third portion of the flat sheet of metal which is to be bent. A cleat 25 is screwed or otherwise fastened to the grooved side of the bar 20 and constitutes a forming shoulder which is cooperable with an associative corner notch 26 provided in the complementary bending and clenching bar 27. The effective clenching surface or face of said bar 27 is denoted by the numeral 28 and another surface is provided with suitably mounted safety clips or brackets 29 which serve in preventing displacement of the completely bent S-clip during the operational steps necessary in turning, bending and clenching to final shape. The bar 27, like the bar 20, is substantially polygonal in cross sectional form and is in spaced parallelism to said bar 20. Attention is now directed to a third oscillatory rocker bar, the same denoted by the numeral 30. This is a square in cross sectional form and is mounted for oscillation between coacting stub-shafts 13 and 17, as brought out in Figure 1. One face of the bar 30 is provided with a bending, clenching and folding blade 31 which is fastened in place by screws or the like 32 and spacing washers 33. The free swingable edge portion of the blade is beveled and thus sharpened, as at 34.

In operation the respective oscillatory bars are in the horizontal positions shown in Figure 3. At this time the handle or lever 19 is to the left and all bars are geared together for simultaneous and sequential operation; that is, operation in successive as well as progressively sequential steps. With the machine set up for use as shown in Figure 3 the work, a rectangular sheet of bendable tin 24 is inserted in the retention pocket formed by the groove 22 and holding and forming plate 23. Approximately one third of the area of the work is thus inserted to take the perpendicular position shown in Figure 3. The lever 19 is swung in a direction from left to right until it takes the position seen in Figure 4. In the latter position, which is the second stage, the first bending step is accomplished. The blade 31 moves around approximately one half-circle (slightly less than 180 degrees) and at the same time the bar 20 moves in a half-circle in an opposite direction, the two parts approaching each other and thus taking the positions shown progressively in Figures 3 and 4. When the free edge portion of the work sheet 24 swings through the path of movement of the bending and clenching blade 31, the latter serves to turn a predetermined portion over the forming edge of the plate 23 and when the parts come to rest, as shown in Figure 4, a U-bend is thus formed in the work. Then, by moving the handle 19 back to its original position, that is from the low position seen at the right in Figure 4, to the original positions shown in Figures 3 and 5, the bendable edge portion 35 (see Figure 4) is acted upon, and a second bend is thus formed, this bend being in a direction opposite to the first bend, whereby to fashion the complete S-shaped clip illustrated in Figure 7. It follows that moving the handle in one direction operates the gears and oscillatory bars to first form a U-bend along one edge of a rectangular strip, and moving the handle back to its original starting position, through the gears and bars, serves to form a return bend in an opposite di-

rection, thus producing with expediency and efficiency the clip illustrated partly in Figure 7. These clips are bent in all sorts of ways in the trade as of today, but I find that by having a simple triple bar frame structure with gears and handle and properly shaping the coacting surfaces of the bars and bringing them into relationship under suitably established principles, an effective turning and bending brake is thus provided.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials or rearrangement of parts may be resorted to in actual practice so long as no departure is made from the invention as claimed.

Having described the invention, what is claimed as new is:

1. An S-clip making brake of the class described comprising a frame structure embodying a pair of spaced parallel end members forming uprights, a plurality of spaced parallel bars mounted for oscillatory movements between said uprights, said bars having journal forming stub-shafts at their ends mounted for operation in bearings in the uprights, said stub-shafts being provided with intermeshing gears, and an operating handle for one of the stub-shafts for simultaneously turning all gears and rocking the bars back and forth, there being three such bars, the central bar constituting a work holding, turning and forming mandrel, one of the outer bars serving to bend and clench a bendable free edge portion of the work against a predetermined surface of the mandrel for purposes of defining a U-bend, the remaining bar serving to coact with the remaining bendable edge portion of the work for purposes of defining a return bend opposite to the first bend, whereby to define an S-shaped piece of work.
2. In an S-clip bending brake of the class described, a pair of relatively stationary uprights, an oscillatory work holding and forming bar mounted for operation between said uprights, said bar being provided on one side with a pocket for reception of an edge portion of the work to be held and bent, being provided on the same side with a longitudinally extending outstanding forming shoulder, the edge portion of the pocket also constituting a forming shoulder, a second oscillatory bar mounted in spaced parallelism between the uprights and alongside of the first bar and provided with a rigid work bending blade engageable with a bendable free edge portion of the work in a manner to form a U-shaped bend in the latter, a third bar mounted for oscillation between the uprights and on an opposite side of first named bar, said third bar serving to engage the remaining free edge portion of the work in a manner to transform same into a second U-shaped bend reversed in position to said first U-shaped bend, all three of said bars being geared together for simultaneous and progressive oscillatory coaction, and a single operating handle for alternately turning the gears back and forth through substantially semi-circular paths for purposes of progressively bending said edge portions of the work, whereby to provide a double bent workpiece which is substantially S-shaped in cross sectional form.

3. A two-way bending, reverse folding, brake for transforming a flat work piece into an S-clip of the class shown and described comprising a relatively stationary frame embodying spaced parallel uprights, a horizontally disposed forming bar suspended and mounted for oscillation between said uprights, said bar having a lengthwise pocket into which one edge of said work piece is placed edgewise and held so that said work piece may be rocked and swung first in one direction and then alternately in an opposite direction, one longitudinal edge portion of said pocket constituting a creasing member to form a bight in that edge portion of the work piece projecting beyond said pocket, a gear fixed on one end of said forming bar, a first stage bending, folding and pressure bar also mounted horizontally for oscillation between said uprights and situated in parallelism outwardly of said forming bar, a pressure applying and folding blade carried by said pressure bar and swingable toward and then away from the pocket to fashion and produce the first fold of the work piece, a gear fixed on said pressure bar and in constant mesh with said first-named gear, a second horizontally disposed pressure applying and folding bar mounted for oscillation between said uprights and situated in parallelism on the other side of said work holding and forming bar, movable toward and from the latter and functioning to form a second bight, opposite from the first-named bight, and to reversely fashion and produce the remaining fold of said work piece, and a third gear, the latter fixed on said second pressure bar and in mesh with said first-named gear.

4. A two-way bending, reverse folding, brake for transforming a flat work piece into an S-clip of the class shown and described comprising a relatively stationary frame embodying spaced parallel uprights, a horizontally disposed forming bar suspended and mounted for oscillation between said uprights, said bar having a lengthwise pocket into which one edge of said work piece is placed edgewise and held so that said work piece may be rocked and swung first in one direction and then alternately in an opposite direction, one longitudinal edge portion of said pocket constituting a creasing member to form a bight in that edge portion of the work piece projecting beyond said pocket, a gear fixed on one end of said forming bar, a first stage bending, folding and pressure bar also mounted horizontally for oscillation between said uprights and situated in parallelism outwardly of said forming bar, a pressure applying and folding blade carried by said pressure bar and swingable toward and then away from the pocket to fashion and produce the first fold of the work piece, a gear fixed on said pressure bar and in constant mesh with said first-named gear, a second horizontally disposed pressure applying and folding bar mounted for oscillation between said uprights and situated in parallelism on the other side of said work holding and forming bar, movable toward and from the latter and functioning to form a second bight, opposite from the first-named bight, and to reversely fashion and produce the remaining fold of said work piece, and a third gear, the latter fixed on said second pressure bar and in mesh with said first-named gear, all of said bars being polygonal in cross-section.

5. A two-way bending reverse folding brake for transforming a flat work piece into an S-clip of the class shown and described comprising a relatively stationary frame embodying

spaced parallel uprights, a horizontally disposed forming bar suspended and mounted for oscillation between said uprights, said bar having a lengthwise pocket into which one edge of said work piece is placed edgewise and held so that said work piece may be rocked and swung first in one direction and then alternately in an opposite direction, one longitudinal edge portion of said pocket constituting a creasing member to form a bight in that edge portion of the work piece projecting beyond said pocket, a gear fixed on one end of said forming bar, a first stage bending, folding and pressure bar also mounted horizontally for oscillation between said uprights and situated in parallelism outwardly of said forming bar, a pressure applying and folding blade carried by said pressure bar and swingable toward and then away from the pocket to fashion and produce the first fold of the work piece, a gear fixed on said pressure bar and in constant mesh with said first-named gear, a second horizontally disposed pressure applying and folding bar mounted for oscillation between said uprights and situated in parallelism on the other side of said work holding and forming bar, movable toward and from the latter and functioning to form a second bight opposite from the first-named bight and to reversely fashion and produce the remaining fold of said work piece, and a third gear, the latter fixed on said second pressure bar and in mesh with said first-named gear, all of said bars being polygonal in cross-section and disposed in substantially the same plane.

6. A two-way bending reverse folding brake for transforming a flat work piece into an S-clip of the class shown and described comprising a relatively stationary frame embodying spaced parallel uprights, a horizontally disposed forming bar suspended and mounted for oscillation between said uprights, said bar having a lengthwise pocket into which one edge of said work piece is placed edgewise and held so that said work piece may be rocked and swung first in one direction and then alternately in an opposite direction, one longitudinal edge portion of said pocket constituting a creasing member to form a bight in that edge portion of the work piece projecting beyond said pocket, a gear fixed on one end of said forming bar, a first stage bending, folding and pressure bar also mounted horizontally for oscillation between said uprights and situated in parallelism outwardly of said forming bar, a pressure applying and folding blade carried by said pressure bar and swingable toward and then away from the pocket to fashion and produce the first fold of the work piece, a gear fixed on said pressure bar and in constant mesh with said first-named gear, a second horizontally disposed pressure applying and folding bar mounted for oscillation between said uprights and situated in parallelism on the other side of said work holding and forming bar, movable toward and from the latter and functioning to form a second bight opposite from the first-named bight and to reversely fashion and produce the remaining fold of said work piece, and a third gear, the latter fixed on said second pressure bar and in mesh with said first-named gear, all of said bars being polygonal in cross-section and disposed in substantially the same plane, and all three of said gears being of identical construction, aligned and disposed on a level approximately in the plane of said bars.

7. The structure defined in claim 6, together with brackets carried by said second pressure and

folding bar constituting fingers adapted to reach over the work piece at the finish of said second folding step to prevent displacement of said work piece from said pocket.

8. A two-way bending reverse folding brake for transforming a flat work piece into an S-clip of the class shown and described comprising a relatively stationary frame embodying spaced parallel uprights, a horizontally disposed forming bar suspended and mounted for oscillation between said uprights, said bar having a lengthwise pocket into which one edge of said work piece is placed edgewise and held so that said work piece may be rocked and swung first in one direction and then alternately in an opposite direction, one longitudinal edge portion of said pocket constituting a creasing member to form a bight in that edge portion of the work piece projecting beyond said pocket, a gear fixed on one end of said forming bar, a first stage bending, folding and pressure bar also mounted horizontally for oscillation between said uprights and situated in parallelism outwardly of said forming bar, a pressure applying and folding blade carried by said pressure bar and swingable toward and then away from the pocket to fashion and produce the first fold of the work piece, a gear fixed on said pressure bar and in constant mesh with said first-named gear, a second horizontally disposed pressure applying and folding bar mounted for oscillation between said uprights and situated in parallelism on the other side of said work holding and forming bar, movable toward and from the latter and functioning to form a second bight opposite from the first-named bight and to reversely fashion and produce the remaining fold of said work piece, and a third gear, the latter fixed on said second pressure bar and in mesh with said first-named gear, all of said bars being polygonal in cross-section and disposed in substantially the same plane, and a single handle directly associated with said second-named gear for operating all three gears in a manner to rock said bar in predetermined directions and progressive order.

9. A two-way bending reverse folding brake for transforming a flat rectangular work piece into an S-clip of the style shown and described comprising a pair of spaced parallel end members, three bars having end journals mounted for oscillation in bearings provided therefor in said end members, all of said bars being on the same level and polygonal in cross-section, a train of three aligned timing and bar rocking gears located exteriorly of and in contact with one of said end members and secured to corresponding journals on the respective three bars, all of said gears being identical, disposed in the same horizontal plane and in substantially the same plane occupied by said bars, a handle rigidly mounted on one of said journals adjacent to but clear of

said gears, there being a central bar having work piece holding and forming facilities, and two successively functioning side bars, and means on the latter two bars for applying pressure and progressively and reversably bending the alternately disposable folds of said work piece.

10. A two-way bending reverse folding brake for transforming a flat rectangular work piece into an S-clip of the style shown and described comprising a pair of spaced parallel end members, three bars having end journals mounted for oscillation in bearings provided therefor in said end members, all of said bars being on the same level and polygonal in cross-section, a train of three aligned timing and bar rocking gears located exteriorly of and in contact with one of said end members and secured to corresponding journals on the respective three bars, all of said gears being identical, disposed in the same horizontal plane and in substantially the same plane occupied by said bars, a handle rigidly mounted on one of said journals adjacent to but clear of said gears, there being a main central bar and two auxiliary side bars, said central bar having one face rabbeted, a plate mounted on said latter bar and parallel with said rabbet and co-acting with the latter in defining a work piece holding pocket and a shoulder, the free edge portion of said plate constituting a crease former, the body portion of said plate constituting a fold former, a blade mounted on one of said side bars and geared to swing toward said central bar as the latter approaches it to bend the work piece and force it against said plate to provide the first fold, said second side bar being geared and timed to engage the work piece as the main bar swings back to its starting position to bend and fashion the second, a reversely disposed, fold.
